UNITED STATES PATENT OFFICE.

WILLIAM C. LEIST AND CHARLES WAGNER, OF WAUSEON, OHIO.

OIL-BURNER.

1,354,314.

Specification of Letters Patent. Patented Sept. 28, 1920.

Application filed July 29, 1919. Serial No. 314,159.

To all whom it may concern:

Be it known that we, WILLIAM C. LEIST and CHARLES WAGNER, citizens of the United States, residing at Wauseon, in the county of Fulton and State of Ohio, have invented certain new and useful Improvements in Oil-Burners, of which the following is a specification.

This invention relates to certain new and useful improvements in a liquid fuel burner and more especially to that type embodying an overlying retort, the principal object residing in a compact, durable and simple structure which may readily be ignited and operated efficiently.

The invention further aims to provide an improved retort construction and feed thereto whereby the fuel may be converted into gas very rapidly and without the danger 20 of explosion.

Further the invention resides in the features of construction and the arrangements and combinations of parts hereafter described and claimed, reference being had to 25 the accompanying drawing wherein.

Figure 1 is a side elevation of the improved burner;

Fig. 2 is a top plan view thereof;

Fig. 3 is a vertical longitudinal section 30 through the burner on line 3—3 of Fig. 2;

Fig. 4 is a horizontal section thereof on line 4—4 of Fig. 3;

Fig. 5 is a transverse vertical section on line 5—5 of Fig. 3; and

Fig. 6 is a section view of the burner on a horizontal plane beneath that of Fig. 4, as indicated at line 6—6.

Referring more in detail to the disclosure, the numeral 1 designates the burner base for 40 the burner body which is composed of two sections 2 and 3, the lower section 2 having a depending, centrally located standard or post 4 secured to the base by screw 5 and serving to space the burner above the base.

The upper section 3 is in the form of a hollow or channeled ring having its opened, bottom side seating on the lower section where it is positioned by a pair of concentric ribs 6 on said lower section. A horizontal 45 conduit or mixing tube extends diametrically through the lower burner section and branches off at its inner end, discharging upwardly between the ribs 6 into the channel or annular chamber 8 of the upper burner

50 section. This latter section is formed in its upper face with concentric semi-circular jet

openings or slots 9, the same terminating in alined radial grooves 11 formed in said upper section.

The overlying retort 10 is disposed above 60 the burner and the grooves 11, extending down into the latter, and comprises parallel passages 12 and 13 containing bundles of small fine wires 14 whereby the liquid fuel passing thereover is more readily vaporized. 65 These passages or conduits communicate at their inner ends through a chamber 15 filled with asbestos 16 which is accessible upon removal of plug 17. The opposite end of the return conduit 13 communicates through 70 vertical conduit 18 with a horizontal chamber 19 opposing or alined with the mixing tube 7. These conduits 12, 13, 18 and 19 are preferably formed in an integral, unitary casting, and in one end of chamber 19 is secured a nozzle 20 for directing the vaporized fuel into the mixing tube or chamber where if commingles with air drawn in through the space between the nozzle and mixing chamber. The nozzle is formed with a valve seat 75 on which engages the needle valve 21 which has its stem 22 threaded through the stuffing box 23 in the opposite end of chamber 19.

The conduit casting is formed with a threaded nipple 24 at its inlet side and in 80 this nipple is secured a pipe 25 filled with gravel 26 or the like, which is retained therein by means of two end caps 27. The opposite end of the pipe or chamber 25 is connected to the fuel line 28. 85

Secured to the base of the burner so as to underlie the chamber 19 and mixing chamber 7 is a Y-shaped ignition or priming tray 29, the branches of the tray or pan straddling the post 4 to effect rapid heating of the 90 burner for starting.

In operation, the fuel line is opened and the liquid fuel trickles through the gravel and wire fillings, and the needle valve 21 is unseated temporarily to permit the fuel oil 100 dropping from the nozzle into the underlying pan. Valve 21 is closed after sufficient oil has dropped into the pan and the fuel is then ignited to heat the chamber 19 and adjacent portions of the burner sufficient to 105 start vaporization when the needle valve is again opened to discharge the pent up gas into the mixing chamber 7 from which the combustible mixture is discharged through the arcuate jet slots 9 and ignited. From 110 this point on the generation of gas by vapor-

izing the fuel occurs in the overlying retort 10 and the priming pan ceases to function.

It will be noted in this connection that by reason of the jet slots terminating in the 5 grooves 10 the flame is directed at an angle toward the overlying retort to more thoroughly heat the same without overheating as when the full jet extends entirely therebeneath. Furthermore, the asbestos, because 10 of its heat insulating qualities, facilitates the flow of the liquid fuel from the upper conduit to the lower or return conduit without vaporization of the fuel until it reaches the return conduit. However, should excessive 15 gas pressure accumulate in the retort the gravel chamber will prevent its escape to the fuel line.

The construction of the burner retort in a single casting simplifies the manufacture and 20 reduces the number of parts. A pair of oppositely extending ears 30 adjacent the nipple connection 24 provides simple and practical means for mounting the retort, said ears being secured to a bracket arm 31 extending 25 from the upper burner section. Thus, to detach the retort from the burner proper requires only the removal of the screws 32 employed to secure ears 30 to bracket arm 31.

30 What is claimed is:

1. A liquid fuel burner comprising a base, a burner body supported thereon by a centrally located post and provided with arcuate jet slots separated by alined radial 35 grooves, a mixing chamber underlying the body and opening at one end, a one-piece retort overlying the burner body in the alined grooves thereof and having a depending conduit part extending adjacent 40 the opened end of the mixing chamber, a valve-controlled nozzle on the depending conduit part for directing the gas into the mixing chamber, and a priming pan secured to the base and about the body-supporting 45 post.

2. A liquid fuel burner comprising a base, a burner body supported thereon by a centrally located post and provided with arcuate jet slots separated by alined radial 50 grooves, a mixing chamber underlying the body and opening at one end, a one-piece retort overlying the burner body in the alined grooves thereof and having a depending conduit part extending adjacent 55 the opened end of the mixing chamber, a valve-controlled nozzle on the depending conduit part for directing the gas into the mixing chamber, and a gravel-filled chamber connected to the inlet side of the retort.

60 3. A burner comprising a lower section having a substantially diametrical tubular mixing chamber opening laterally at one side of the section and upwardly through the top face of the body section at the opposite side, and a ring-like upper section of

inverted U-section seating on the lower section over the opening from the mixing chamber, said upper section formed with curved jet slots.

4. A burner comprising a body having 70 concentric jet openings terminating in a diametrical groove, and an overlying retort arranged above the groove and having a nozzle part discharging into the body.

5. A burner comprising a ring-like body 75 having arcuate jet slots in one face and a tubular mixing chamber extending diametrically across its opposite face, said chamber at one end entering the body and having its opposite end opening beneath the body 80 adjacent its periphery, the latter being provided above the opened end with a bracket, and a gas supply nozzle supported on the bracket and discharging into the mixing chamber.

6. A burner comprising a ring-like body having arcuate jet slots in one face and a tubular mixing chamber extending diametrically across its opposite face, said chamber at one end entering the body and having its 90 opposite end opening beneath the body adjacent its periphery, the latter being provided above the opened end with a bracket, and an overlying retort secured to the bracket and provided with a nozzle depend- 95 ing to discharge into the mixing chamber.

7. A burner comprising a ring-like body having arcuate jet slots in one face and a tubular mixing chamber extending diametrically across its opposite face, said chamber 100 at one end entering the body and having its opposite end opening beneath the body adjacent its periphery, the latter being provided above the opened end with a bracket, a unitary retort structure extending across the 105 first face of the body and secured to the bracket, said retort structure having two bores therethrough opening into a communicating chamber, a closure member for the chamber, a filler of fibrous material for the 110 chamber compressed therein by the closure member, and a nozzle connected to the retort and discharging into the mixing chamber.

8. A burner comprising a ring-like body 115 having arcuate jet slots in one face and a tubular mixing chamber extending diametrically across its opposite face, said chamber at one end entering the body and having its opposite end opening beneath the body ad- 120 jacent its periphery, the latter being provided above the opened end with a bracket, spaced bracket parts extending laterally from the body, an overlying retort having oppositely extending ears engaging the 125 bracket parts, a nozzle depending between the latter for discharging into the mixing chamber.

9. A burner comprising a ring-like body having arcuate jet slots in one face and a 130

tubular mixing chamber extending diametrically across its opposite face, said chamber at one end entering the body and having its opposite end opening beneath the body adjacent its periphery, the latter being provided above the opened end with a bracket, a unitary retort structure overlying the body and having a nozzle depending to one side thereof for discharge into the mixing chamber, a valve in the nozzle having its operating stem extending outwardly of the body, and a filter pipe connected to the re-

tort and extending lengthwise of and above the valve stem.

10. A burner body comprising an annular base, an annular jet member seated thereon formed with arcuate jet openings interrupted by aligned radial grooves, and means in the grooves for securing the jet member to the base. 15

In testimony whereof we affix our signatures.

WILLIAM C. LEIST.
CHARLES WAGNER.
